UNITED STATES PATENT OFFICE.

JOHN GEORGE BODENSTEIN, OF STAATSBURG, NEW YORK.

INSERTED-TOOTH FASTENING FOR ICE-PLOWS.

SPECIFICATION forming part of Letters Patent No. 295,724, dated March 25, 1884.

Application filed January 9, 1884. (Model.)

To all whom it may concern:

Be it known that I, JOHN GEORGE BODENSTEIN, of Staatsburg, in the county of Dutchess and State of New York, have invented certain new and useful Improvements in Inserted-Tooth Fastenings for Ice-Plows, of which the following is a full, clear, and exact description.

Reference is to be had to the accompanying drawings, forming part of this specification, in which similar letters of reference indicate corresponding parts in all the figures.

Figure 1 is a side elevation of a part of an ice-plow to which my improvement has been applied, parts being broken away. Fig. 2 is a sectional front elevation of the same, taken through the line *x x*, Fig. 1. Fig. 3 is a perspective view of one part of the fastening.

The object of this invention is to promote convenience and security in fastening inserted teeth to the beams of ice-plows, and allow the said teeth to be readily adjusted.

The invention consists in an inserted tooth fastening for ice-plows, constructed with a stop-plate having a perforated L-shaped head at its upper end and a shoulder at its lower end, and a wedge-key having a screw and a nut upon its upper end, to adapt it to be inserted between the parts of a plow-beam to clamp an inserted tooth against the edge of a plow-plate section, as will be hereinafter fully described.

A represents the plow-beam, which is made in two parts placed at such a distance apart as to receive between them the plow-plate sections B, and which are secured to each other and to the said plate-sections B by bolts C.

The forward edges of the plate-sections B are concaved upon the arcs of circles, and are grooved to receive the tongues B', formed upon the convexed edges of the teeth D, so as to hold the said teeth from lateral movement. The forward edge of each tooth D is concaved, and against it rests the convexed rear edge of the stop-plate E, which is made of such a thickness as to fit between the parts of the beam A.

Upon the upper end of the stop-plate E is formed an L-head, E', which rests upon the upper edges of the parts of the beam A. Upon one side of the lower end of the stop-plate E is formed a shoulder, E², which rests against the lower edge of one of the parts of the beam

A. By this construction the stop-plate E will be held from moving either upward or downward. The lower end of the stop-plate E is beveled, so that it will not offer an obstruction to the ice-chips. The stop-plate E is made wider toward its upper end, to give the forward edge of the said plate a forward inclination upward.

F is a wedge-key, which tapers upward from its lower end, and has its rear edge straight, to fit against the straight forward edge of the stop-plate E. The forward edge of the wedge-key F is concaved to fit against the convexed rear edge of a plow-plate section, B. Upon the upper end of the wedge-key F is formed a screw, F', which passes through a hole in the forwardly-projecting end of the L-head E' of the stop-plate E, and has a nut, G, screwed upon its upper end. With this construction, by tightening the nut G the wedge-key F will be drawn upward, forcing the stop-plate E back and the tooth D against the forward edge of the plow-plate section B, and clamping the tooth D securely in place. By loosening the nut G and driving the wedge-key F downward, the tooth D will be released and can be adjusted or detached and replaced, as may be required.

Having thus described my invention, what I claim as new, and desire to secure by Letters Patent, is—

1. An inserted-tooth fastening for ice-plows constructed substantially as herein shown and described, and consisting of the stop-plate E, having a perforated L-head, E', at its upper end and a shoulder, E², at its lower end, and the wedge-key F, having screw F' and nut G, substantially as herein shown and described.

2. The combination, with the plow-beam A, the plow-plate sections B, and the inserted tooth D, of the stop-plate E, having a perforated L-head, E', at its upper end and a shoulder, E², at its lower end, and the wedge-key F, having screw F' and nut G, substantially as herein shown and described, whereby the inserted tooth will be securely held and can be readily adjusted and replaced, as set forth.

JOHN GEORGE BODENSTEIN.
